UNITED STATES PATENT OFFICE

151,582

DESIGN FOR A CHILD'S CART

Jesse H. Bates, Wauwatosa, Wis.

Application August 7, 1946, Serial No. 132,347

Term of patent 7 years

(Cl. D34—15)

To all whom it may concern:

Be it known that I, Jesse H. Bates, a citizen of the United States residing at Wauwatosa, in the county of Milwaukee and State of Wisconsin, have invented a new, original, and ornamental Design for a Child's Cart, of which the following is a specification, reference being had to the accompanying drawing, forming a part thereof, and in which:

Fig. 1 is a top plan view; and

I claim:

The ornamental design for a child's cart, substantially as shown.

JESSE H. BATES.
